[57] CLAIM

The ornamental design for auxiliary vehicle stop light, as shown and described.

DESCRIPTION

FIG. 1 is a top plan view of auxiliary vehicle stop light, showing our design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a top, front perspective view thereof;

FIG. 7 is an enlarged, fragmentary top plan view of the portion of the lamp enclosed by lines 7—7 in FIG. 1;

FIG. 8 is an enlarged cross-sectional view as taken on

line 8—8 of FIG. 7;

FIG. 9 is an enlarged cross-sectional view thereof as

taken along line 9—9 of FIG. 2.
